CLAIM

The ornamental design for an air-conditioning outdoor unit, as shown and described.

DESCRIPTION

1. Air-conditioning outdoor unit

1.1 : Front

1.2 : Back

1.3 : Left

1.4 : Right

1.5 : Top

1.6 : Bottom

1.7 : Perspective

1.1 is a front elevation view of an air-conditioning outdoor unit showing our new design; 1.2 is a back elevation view thereof; 1.3 is a left side elevation view thereof; 1.4 is a right side elevation view thereof; 1.5 is a top plan view thereof; 1.6 is a bottom plan view thereof; and 1.7 is a perspective view thereof.

(Continued)

The broken lines in FIGS. 1.1-1.7 depict portions of the air-conditioning outdoor unit that form no part of the claimed design.

1 Claim, 5 Drawing Sheets
